FRANK W. ROLLER, OF EAST ORANGE, NEW JERSEY, ASSIGNOR TO ROLLER-SMITH COMPANY, A CORPORATION OF NEW YORK.

CIRCUIT-CONTROLLING APPARATUS.

1,124,809.

Specification of Letters Patent. Patented Jan. 12, 1915.

Application filed October 18, 1911. Serial No. 655,377.

To all whom it may concern:

Be it known that I, FRANK W. ROLLER, a citizen of the United States, residing at East Orange, in the county of Essex and State of New Jersey, have invented certain new and useful Improvements in Circuit-Controlling Apparatus, of which the following is a full, clear, and exact specification.

This invention relates to the regulation of apparatus through the instrumentality of electric circuits and may, therefore, be said to relate to electric regulators. It will be understood, however, that although adapted to regulate the conditions in an electric circuit, it may be applied to the regulation of conditions in various systems and apparatus and in those which are not electrical.

The main object of the invention is to provide apparatus of the character described which shall be certain and positive in its operation.

It is a further object of the invention to provide a circuit making and breaking device adapted for use in such regulators, wherein the contacts will have a minimum of deterioration and the circuit will be positively opened or positively closed, there being no uncertainty and vibration between the two conditions. On the contrary, after the circuit is closed it remains closed undisturbed by slight changes in the operating means or vibration of the parts, and when it has been opened it remains open regardless of slight changes or vibration. There is a margin in both the closure and in the break so that the uncertainty of either condition due to transient or insignificant variations is avoided, while when there is a radical departure from desired conditions requiring an opening or closing of the circuit, as the case may be, the circuit is opened or closed readily and certainly.

Ancillary and other objects of the invention will appear hereinafter.

In the accompanying drawings which illustrate the invention, Figure 1 is a top plan view of circuit making and breaking apparatus (certain of the parts being omitted for the sake of clearness), the circuit connections thereto and the remainder of the regulating apparatus being shown diagrammatically; and Fig. 2 is a side elevation of the circuit making and breaking apparatus of Fig. 1, the actuating means therefor being shown in section, the middle

portion of this operating means being broken away to economize space in the drawing and certain other of the parts being broken away or removed for the sake of clearness.

Referring to the drawings, an electric furnace of well-known construction comprising the crucible 1 and electrodes 2 and 3 is fed from a suitable supply circuit 4 and 5. Within the crucible is a charge 6. The electrode 2 is adjustable lengthwise in a well-known manner to secure a proper arc gap. The feeding of the electrode 2 is accomplished by means of an electric motor 7 which drives the electrode through a pinion 8 and a rack 9. This motor may be of the series direct-current type, the terminals of the armature being connected to the binding posts 10 and 11, while the terminals of the field are connected to the binding posts 12 and 13. One of the binding posts 13 is connected to the supply terminal 5, while the other binding post 12, to which the other terminal of the motor field is connected, is connected with the switch blade 14 of a reversing switch, the other blade 15 of this switch being connected to the supply wire 4. The contacts 16 and 17 of the reversing switch are connected with one terminal of the motor armature, while the contact 18 is connected with the other terminal of the armature.

The two switch blades 14 and 15 are pivoted to swing in a well-known manner and are insulated from each other although mechanically connected together. These blades are held in open circuit position as shown by means of springs 19. The reversing switch is adapted to be operated by solenoids 20 and 21, having a common plunger 22 from which a rod extends to the blades of the reversing switch to which it is pivoted. Upon energizing the solenoid 21, the plunger and the reversing switch are thrown to the right, while when the solenoid 20 is energized the plunger and reversing switch are thrown to the left.

In order to maintain the proper voltage across the arc in the furnace, conductors 23 and 24 are run from the respective electrodes of the furnace to the binding posts 25 and 26 constituting the terminals of a regulating device for an electric circuit which controls the operation of the motor 7 and so controls the length of arc gap in the fur-

nace. This device may be similar to the well-known moving coil type of voltmeter in that it may comprise a permanent magnet 27 between the poles of which is located a coil of wire 28 mounted upon pivots 29 and 30. Springs 31 and 32 surround these pivots each being at one end connected to a stationary part of the apparatus and the other end mechanically secured to a pivot. Turning of the coil and pivots therefore is opposed by the spring action.

Within the coil and supported in any suitable manner may be located a cylinder 33 of magnetic material.

15. Circuit to the terminals of the coil 28 from the binding posts 25 and 26 is secured by means of the conductors 34 and 35, which are connected with these terminals and with the springs 31 and 32, respectively.

20 Mounted upon the pivot 29 but insulated therefrom is a needle 36 swinging over a scale 37.

The construction thus far described may be made like that of the moving coil type voltmeter above referred to. The needle 36 has a rearward extension 38.

Two arms 39 and 40 unite in a compass joint 41 having its center in line with the pivots 29 and 30. Each of these arms may 30 be of conducting material.

The needle 36 carries a contact 42 which is adapted to engage electrically first with the auxiliary contact 43 and subsequently with the contact 44 as the needle swings to the right. The contact 43 is mounted upon an arm 45 pivoted upon the spindle 46 and normally pressed against the stop 47 by a spring 48 which encircles the spindle 46 and at one end is secured to a stationary part and at the other end is secured to the spindle. The stop 47 is pivoted eccentrically so that the position of the arm 45 may be adjusted by turning the eccentric upon its pivot. To counterbalance the moment due to gravity exerted by the arm 45 upon the spindle 46, a semi-circular counter weight 49 is secured on the spindle and its center of gravity may be shifted by turning it to secure the proper balancing of the weight of the arm 45.

The contact 44 is in the form of a screw and is, therefore, adjustable in the post 50 which is insulated from the arm 39. From this post a conductor 51 leads to an electromagnetic device for controlling the conditions to be regulated, as will be hereinafter referred to. Also a conductor 52 is electrically connected with the arm 39 and therefore with the auxiliary contact 43, this conductor also serving to complete the circuit of the electromagnetic device just referred to under certain conditions.

Upon the arm 40 is mounted apparatus similar to that upon the arm 39, including a contact 53 mounted in an insulated post 54

from which a conductor 55 extends to an electromagnetic device to be presently referred to, an auxiliary contact 55' carried upon a pivoted arm 56 spring pressed by spring 57 against a pivoted eccentric stop 58 and a counter weight 59 for the arm 56.

A conductor 60 is in electrical connection with the arm 40 and the auxiliary contact 55', and affords a means for completing a circuit to a controlling electromagnetic device as will be shortly described. It will be apparent that as the needle 36 swings to the left it will contact first with the auxiliary contact 55' and subsequently with the contact 53. While this regulating device, which is the specific one shown in the drawings, operates according to the principles of a voltmeter in affecting the desired regulation, it will be understood by those skilled in the art that where the conditions warrant it regulation may be accomplished according to the present invention by means of an ammeter; that is, by a device responsive to load current as distinguished from a device responsive to voltage. 75 80 85 90

As has already been set forth, when the solenoid 21 is energized the motor 7 will be connected to operate in one direction, while when the solenoid 20 is energized the motor will be connected for rotation in the opposite direction and when neither of the solenoids is energized the circuit of the motor will be broken and it will be at a standstill. The circuit of the solenoid 20 is controlled by the spring contacts 61 and that of the solenoid 21 is controlled by the spring contacts 62. Normally the contacts 61 and 62 are open as shown and the solenoids deenergized. They are adapted to be closed by a cam head 63 which closes the contact 61 when swung to the right and the contacts 62 when it is swung to the left. As will be apparent from inspection of the drawings, the closing of either one of these sets of contacts will complete the circuit of its respective solenoid through the battery 64. The cam head 63 is mounted upon a member pivoted at 65 and which comprises the cross piece 66 and the vertical piece 67'. The cross piece 66 is normally held in its 95 100 105 110 115

cross piece 66 is normally held in a horizontal position as shown by means of a weight 68'. To the cross piece 66 is secured an armature 67 for the magnet 68 and an armature 69 for the magnet 70. When the magnet 70 is energized, the right-hand end of the cross piece will be drawn down and the contacts 61 closed while the energization of the magnet 68 will draw down the left-hand end of the cross piece, and close the contacts 62. When neither of the magnets 68 or 70 is energized, the parts will occupy the position as shown in the drawing and both sets of contacts 61 and 62 will be open.

Located at the respective ends of the cross piece 66 are normally open pairs of spring contacts 61 and 62 which will be open.

- contacts 71 and 72. It will be observed that one of the contacts 71 is connected with the conductor 60 and is therefore in electrical connection with the auxiliary contact 55, while the other one of the contacts 71 is connected with the conductor 55 and is therefore in electrical connection with the contact 53. Also the conductor 55 is connected to one terminal of the magnet 68. Similarly the conductors 51 and 52 are respectively connected with the contacts 72 and with the contacts 43 and 44. Also the conductor 51 is connected with one terminal of the magnet 70.
- 15 The terminals of the magnets 68 and 70, other than those connected to the conductors 55 and 51, are connected to one terminal of the battery 64, connection from the other terminal of the battery being made to the 20 rearward extension 38 of the needle 36. It will now appear that if a circuit is made through the magnet 70 and the conductor 51, the parts being in the position as shown, the right end of the cross piece 66 will be 25 drawn downwardly and will close the contacts 72. The arrangements being such that the closing of the contacts 72 also completes a circuit through the magnet 70, it will be 30 apparent that the magnet cannot be deenergized by simply breaking the circuit through the conductor 51, but the magnet will remain energized until not only that connection is broken but also the connection through the conductor 52 and contacts 72 is 35 broken. When both of these connections have been broken, however, the magnet will be deenergized and the cross piece assume the position as shown in the drawings with the contacts 72 open. Inasmuch as the 40 energization of the magnet 70 through the conductor 52 depends upon the closing of the contact 72, it will be apparent that the magnet cannot be so energized until after it has been initially energized through the 45 conductor 51, but after such initial energization the circuit of the magnet 70 can remain closed until after that through the conductor 51 has been broken. Similarly, the left-hand end of the cross piece 66 controls the contacts 71 and the energization of the magnet 68 is effected in a similar manner by means of the conductors 55, 50 and the contacts 71.
- 50 The arms 39 and 40 may be turned upon their compass joint before referred to, to any desired position, buttons or finger pieces 73 and 74 being provided at the outward ends of the respective arms 39 and 40 to facilitate their adjustment.
- 55 The operation of the apparatus may be outlined as follows: The apparatus and connections being arranged as described, the arms 39 and 40 will be adjusted to such positions respectively that contact will be effected between the contacts 42 and 44 at a certain low limit of voltage across the arc, while contact between the contacts 53 and 42 will be effected when a certain high limit of voltage has been reached. Arms 39 and 40 may be readily positioned by reference to 60 the scale 37 over which the arms move, while the needle or movable contact member 36 may serve to indicate the voltage across the arc. So long as the needle remains in a central position as shown in the drawings, the parts of the apparatus will remain in the positions shown and the electrodes will remain stationary. If, for any reason, however, the voltage across the electrodes should decrease, the needle 36 would swing to the 65 right in accordance with well-known laws, such as are applied in well-known electrical instruments. When the voltage has decreased sufficiently, the contact 42 will engage with the contact 43, thereby establishing connection from one terminal of the battery 64 through the needle, contacts 42 and 43, arm 45, arm 39 and conductor 52 to one of the contacts 72. The circuit is, however, 70 broken at this point, the contacts 72 being open, so that no energization of the magnet 70 takes place. If, however, the decrease in voltage continues, the needle will continue to swing to the right until finally the contact 72 will be in electrical engagement with the 75 contact 44. Circuit may now be traced from one terminal of the battery 64 through the needle, contact 42, contact 44, post 50, conductor 51 and magnet 70 to the other terminal of the battery. The magnet 70 is 80 therefore energized and draws down the right-hand end of the cross piece 66. This closes the contacts 72 so that not only is the circuit of the magnet 70 now made through the contact 44, as just described, but circuit 85 is also completed from the contact 42 through contact 43, arm 45, arm 39, conductor 52 and contacts 72. The energization of the magnet 70 has also thrown the cam head 63 to the right, thereby closing the 90 circuit of the solenoid 20 and shifting the reversing switch to the left. This closes the circuit of the motor 7 with the field and armature in such relation that the motor rotates in a direction to draw the electrode 95 2 outwardly and increase the arc gap. This will cause an increase of voltage across the arc gap, whereupon the needle 36 will tend to swing to the left. The operation of the motor as just described, however, will continue until the circuit of the magnet 70 is broken. This circuit remains closed through the contacts 72 until after the needle has receded to the left far enough to break the contact between the contacts 42 and 43. 100 The magnet 70 will then be deenergized, the cross piece 66 will return to the horizontal position as shown in the drawing, the contacts 61 will be opened, the magnet 20 will be deenergized, the reversing switch will 105 110 115 120 125 130 135 140

come into neutral position, and the motor will stop. Similarly, if the voltage across the arc should rise, the needle 36 would swing to the left, first engaging with the auxiliary contact 55'. This, however, will 5 complete no circuit as the contacts 71 are open.

As the arc voltage still increases, the needle will continue its swing to the left 10 until finally electrical engagement is made between the contact 42 and the contact 53. Circuit will then be initially made, by means of the conductor 55, through the magnet 68. The left-hand end of the cross 15 piece 66 will be drawn down, closing the contacts 71 and completing the circuit of the magnet 68 by way of the conductor 60 and auxiliary contact 55'. When the left-hand end of the cross bar 66 is drawn down, the 20 contact 62 will be closed, thereby energizing the solenoid 21, throwing the reversing switch to the right and connecting up the motor 7 so that the armature and field are connected in reverse relation to that when 25 the reversing switch was thrown to the left. The motor will then rotate in such direction as to feed the electrode forward and decrease the voltage across the arc gap. As the voltage 30 is thus decreased the needle will be retracted toward the right, contact being first broken at the contact 53. This, however, does not serve to deenergize the magnet 68 as its circuit is still maintained through the auxiliary contact 55' and the contact 71. 35 When the needle is swung to the right far enough, however, so that the contacts 42 and 53' are disengaged, the circuit of the magnet 68 is broken, whereupon the cross piece 66 swings into horizontal position, as shown 40 in the drawings, the contacts 62 and 71 are opened, and the motor stops.

It will be observed from the foregoing that as the movable contact member or needle, which swings in accordance with the 45 conditions to be regulated, causes an initial closing of the circuits for either of the magnets 68 or 70 according as the high or low limit of voltage has been reached, and thereupon sets in operation regulating apparatus which operates in a manner tending to restore the conditions to their desired state. As these conditions are restored, however, and the needle in response thereto recedes, circuit is not broken at the contact 50 at which the circuit for the magnet was originally made but such circuit is continued through an auxiliary contact until the contact actuated by the movable member is at a considerable distance from the position at 55 which the circuit is initially made. The circuit having been broken at this auxiliary contact, coöperating contacts controlled by the magnet are opened so that circuit cannot again be made until the needle is moved 60 to such position as to close contact through

the initial circuit making contacts, as referred to. By this arrangement, chattering of the contacts with consequent arcing and uncertainty of contact, as well as chattering of the apparatus controlled by the magnets 70 68 and 70, is done away with. There is a minimum of arcing at the contacts, the circuit to set the motor in operation is not closed until there has been a radical change 75 in conditions requiring correction, and when this circuit has been made it is retained until the conditions have been restored by a considerable amount so that only a radical departure from desired conditions will cause the regulating apparatus to again operate, 80 slight vibrations and small and transient variations being of no effect to set the regulating apparatus in operation. For example, when the needle 36 has moved to the right so as to establish the initial circuit 85 through the contact 44 and the motor has been set in operation to increase the voltage in the electric furnace, such increase in voltage will cause the needle to swing to the left and if the auxiliary contact 43 were 90 not present, as soon as the contacts 42 had the left the contact 44, the circuit through the magnet 70 would be broken and the motor would stop. The contact 42 would then lie just clear of the contact 44 and any 95 vibration of parts or any transient or slight decrease of voltage would bring the contacts 42 and 44 together again, thus setting the motor in operation until the contact 42 again cleared the contact 44 (or before the 100 motor could be set in operation there might be a temporary slight increase of voltage which would separate the contacts 42 and 44). There would thus be uncertainty of 105 operation of the apparatus and chattering and arcing at the contacts. With the auxiliary contact, however, the circuit of the magnet 70, after having been initially closed at the contact 44, is maintained until there has been a considerable increase in voltage and recession of the needle, and then, 110 when the circuit is broken between the contacts 42 and 43, the circuit is opened up at the contact 72, thereby preventing any closure of the circuit if the contact 42, for any reason, should be moved back into engagement with the contact 43, such closure not being possible until there has been such a radical decrease in voltage that the contact 42 will be carried into electrical engagement with the contact 44 so as to initially close the circuit of the magnet 70. Thus, 115 certain and positive operation of the apparatus is secured upon such radical changes and conditions as require correction, while 120 chattering, arcing and uncertainty of operation are done away with.

While the invention has been illustrated in what is considered one of its best applications, it may have other embodiments 125 130

without departing from its spirit and is not, therefore, limited to the structure shown in the drawings.

What I claim is:

5. 1. An electric circuit making and breaking device comprising in combination a contact member adapted to be moved in opposite directions to engage and disengage contacts, an additional contact engaged and disengaged by increased movement of said member beyond the position for engaging and disengaging said first-named contacts, and means for initially completing the electrical circuit at certain of said contacts and breaking said circuit at another of said contacts.
- 10 2. An electric circuit making and breaking device comprising in combination a contact member adapted to be moved in different directions to engage and disengage contacts, an additional contact engaged and disengaged by increased movement of said member beyond the position for engaging and disengaging said first-named contacts, and means for causing the initial completion of said circuit at certain of said contacts when said member is moved in one direction and breaking of said circuit at certain other of said contacts when said member is moved in the other direction and for preventing the initial completion of the circuit at the breaking contacts or the breaking of the circuit at the making contacts.
- 15 3. In a circuit making and breaking device, the combination with a contact member movable to make and break a circuit, contacts successively moved into electrical connection by said member as it is moved in one direction and successively disengaged from electrical connection in inverse order as said member is moved in the reverse direction, and means for initially completing the circuit upon an electrical contact connection subsequent to the first as said member is moved in the direction to complete the circuit and breaking the circuit upon an electrical contact disconnection subsequent to the first as said member is moved in the opposite direction.
- 20 4. In a circuit making and breaking device, the combination with the contact member movable in opposite directions to make and break a circuit, of a contact mounted thereon, a second contact in the path of the aforesaid contact and adapted to initially complete the circuit when in electrical connection with said contact upon said movable member, an auxiliary contact making contact in advance of and disengaging contact subsequent to the aforesaid contacts, and means for preventing initial completion of the circuit at said auxiliary contact and preventing breaking of said circuit upon electrical disconnection of said second contact and the contact upon said movable member.

5. In a circuit making and breaking device, the combination with a contact member, movable in opposite directions to make and break a circuit, of a contact mounted thereon, a second contact in the path of the aforesaid contact, an auxiliary contact making contact in advance of and disengaging contact subsequent to the said second contact, an electromagnetic device having its circuit initially closed through electrical connection of said contact upon said member and said second contact, and contacts controlled by the energization of said electromagnetic device and controlling a circuit through said electromagnetic device and said auxiliary contact.

6. The combination with a contact member movable in opposite directions to make and break a circuit, of a contact mounted upon said member, a second contact in the path of the aforesaid contact and adapted to initially close the circuit when in electrical connection with said contact upon said movable member, an auxiliary contact making contact in advance of and disengaging contact subsequent to making and breaking respectively of the electrical connection between the aforesaid contacts; an electromagnetic device having its circuit initially closed through electrical connection of said contact upon said member and said second contact, contacts controlled by the energization of said electromagnetic device and controlling a circuit through said electromagnetic device and said auxiliary contact, and other contacts located in another circuit and controlled by said electromagnetic device.

7. The combination with a contact member movable in opposite directions, contacts at each end of the movement of said member adapted to have a circuit closed through them by said member, the contacts operated by said member at each end of its travel comprising contacts through which a circuit is initially made and an auxiliary contact making contact in advance of and disengaging contact subsequent to the said contacts for initially making the circuit, and means corresponding to the contacts at each end of the travel of said member for preventing initial closing of the circuit at the auxiliary contact and preventing breaking of the circuit upon the disconnection of the contacts for initially making the circuit.

8. The combination with a contact carrying member movable in opposite directions, of a second contact carrying member, contacts carried by said members and comprising initial making contacts and auxiliary breaking contacts, and means comprising a circuit having connections adapted to initially close said circuit upon electrical connection of the said making contacts subsequent to said breaking contacts having been

engaged with each other and to break said circuit at said auxiliary contacts subsequent to the electrical disconnection of the contacts for initially making said circuit.

- 5 9. The combination with a contact member movable in opposite directions, contacts at each end of the movement of said member adapted to have a circuit closed through them by said member, the contacts operated 10 by said member at each end of its travel comprising a contact through which a circuit is initially made and also an auxiliary contact which breaks contact subsequent to the breaking of contact at said contact for 15 initially making the circuit, an electromagnetic device corresponding to the contacts at each end of the travel of said member, each of said devices having its circuit initially closed through the initially closing contacts 20 at its respective end of the travel of said contact member, contacts controlled by the energization of each of said devices and controlling a circuit through the corresponding electromagnetic device and auxiliary 25 contact.

10. The combination with a circuit for electric current, of a contact member movable through the electro-magnetic influence of the current in said circuit, contacts successively moved into engagement by said member as it is moved in one direction and successively disengaged in inverse order as said member is moved in the reverse direction, and an electric circuit having electrical 35 connections initially completing said circuit through a contact engagement subsequent to the first as said member is moved in one direction and permitting breaking of the circuit by a contact disengagement subsequent to the first as said member is moved in the opposite direction.

11. The combination with a contact member movable in opposite directions, of an adjustable arm, a contact carried by said member, a plurality of contacts carried by said arm, the contacts on said arm being successively brought into electrical connection with the contact on said member by movement of said member in one direction, and 50 an electric circuit having connections initially closing said circuit through one of the contacts on said arm and breaking the circuit through another of the contacts on said arm.

55 12. The combination with a contact member movable in opposite directions, of a contact carrying arm, contacts carried by said arm and member and comprising initial closing and auxiliary contacts, the contacts 60 on said arm and movable member being engaged by the movement of said member in

one direction, and a circuit having connections initially closing the circuit through said initial contacts and breaking said circuit subsequent to the disconnection of said 65 initial contacts, and means for adjusting the said auxiliary contact with relation to other of said contacts.

13. The combination of a movable contact element, contacts successively electrically engaged by said element by movement of said element in one direction and successively electrically disengaged by movement of said element in the opposite direction, electro-magnetic means affected by the 75 engagement and disengagement of said contacts, and means for causing the circuit of said electro-magnetic means to be closed by electrical engagement of one of said successively engaged contacts by the movement 80 of said contact element in one direction and to open said circuit at a different one of said contacts by the movement of said contact element in the opposite direction.

14. The combination of a movable contact element, a pair of contacts successively placed in electrical engagement by movement of said element in one direction, electro-magnetic means the circuit of which is closed by the electrical engagement of the 90 last contact engaged by the movement of said contact element in one direction, and means for causing the opening of said circuit by the disengagement of the last contact disengaged by movement of said contact element in the opposite direction.

15. The combination of a movable contact element, contacts successively electrically engaged by said element by movement of said element in one direction and successively electrically disengaged by movement of said element in the opposite direction, electro-magnetic means affected by the engagement and disengagement of said contacts, and means for causing the circuit of 105 said electro-magnetic means to be closed by electrical engagement of one of said successively engaged contacts by the movement of said contact element in one direction and to open said circuit at a different one of 110 said contacts by the movement of said contact element in the opposite direction, said contact at which said circuit is opened being disengaged subsequently to the disengagement of said contact which closed said 115 circuit.

In testimony whereof I affix my signature, in presence of two witnesses.

FRANK W. ROLLER.
